UNITED STATES PATENT OFFICE.

HARRY J. RICKERT, OF CHICAGO, ILLINOIS.

DEPOSIT AND COLLECTION RECEPTACLE.

1,121,133.

Specification of Letters Patent.

Patented Dec. 15, 1914.

Application filed November 7, 1913. Serial No. 799,737.

To all whom it may concern:

Be it known that I, HARRY J. RICKERT, a citizen of the United States, residing at Chicago, in the county of Cook and State of Illinois, have invented certain new and useful Improvements in Deposit and Collection Receptacles, of which the following is a specification.

This invention relates to deposit and collection receptacles designed more particularly for holding milk bottles, groceries, etc., a receptacle being provided which is mounted in a hole extending through the wall of a building, said receptacle having a door at each end through which access is had to the interior of the receptacle, one of said doors opening to the outside and the other door to the inside of the building.

The invention has for its object to provide the receptacle with a novel and improved means for preventing access thereto from the outside after the milk bottles or other goods have been placed therein by the dealer.

A further object of the invention is to provide a receptacle of the kind stated which is perfectly sanitary, dust and dirt being effectually excluded therefrom.

These objects are attained by means of a combination and arrangement of parts to be hereinafter described and claimed, reference being had to the accompanying drawing, in which—

Figure 1 is a central longitudinal section of the apparatus. Fig. 2 is an elevation thereof, and Fig. 3 is a vertical section on the line 3—3 of Fig. 1.

Referring specifically to the drawing 10 denotes the wall of a building in which is made a hole 11 to receive a casing 12. The hole extends entirely through the wall, and at the ends of the casing are outstanding flanges 13 which fit against the faces of the wall, whereby the casing is held in place and prevented from shifting longitudinally in the hole. The casing opens through both sides of the wall, and it is therefore accessible from the inside as well as from the outside of the building.

That end of the casing 12 which opens into the inside of the building has a hinged door or other suitable closure 14. The other end of the casing, or that end which opens to the outside of the building, also has a hinged door or other suitable closure 15 provided with a latch 16, which may be an

ordinary sliding bolt entering a keeper 17 on the adjacent flange 13. The door 14 may also be provided with a latch.

In the casing 12 is slidably mounted a receptacle 18, the same sliding on the bottom of the casing. The top of the receptacle is open and comes close to the top of the casing, which latter therefore serves as a closure to exclude dirt, etc. The ends of the receptacle are provided with handles 19.

On the inner end of the receptacle 18, or that end which is next to the door 14, is a housing 20 in which is mounted a vertically sliding or gravity latch bolt 21 having a stem 22 which projects from the front of the housing through a vertical slot 23 therein. The latch bolt 21 is adapted to be dropped down to depend from the bottom of the receptacle into a central, longitudinal groove 24 in the bottom of the casing 12 on the inside thereof, said groove being stepped to form longitudinally spaced shoulders 25 and 26, respectively, located near opposite ends of the casing and engageable by the latch bolt.

In operation, the door 14 is opened and the receptacle 18 is withdrawn to receive empty milk bottles. The receptacle is then pushed back into the casing until the latch bolt 21 rests on the first stepped portion of the groove 24, slightly beyond the shoulder 25. The receptacle cannot be pulled entirely out of the casing from the outer end thereof by reason of the shoulder 26, the latch bolt, by engaging said shoulder, limiting the outward movement of the receptacle. The dealer delivering the milk or other goods, opens the door 15, pulls out the receptacle as far as it will go and places the goods therein, after removing the empty bottles. The receptacle is now pushed back as far as it will go, or until the latch bolt drops behind the shoulder 25, whereupon the receptacle is prevented from being pulled out again from the outside, and the goods in the receptacle are housed and safe from theft, removal being possible only by opening the door 14 and sliding the receptacle out of the casing from the inside of the building.

I claim:

1. A deposit and collection receptacle comprising a casing fixed in a wall or other support and opening through opposite sides thereof, said casing having longitudinally spaced shoulders on the inside, a receptacle slidably in the casing, and a latch carried

by the receptacle and adapted to abut against either of the aforesaid shoulders.

2. A deposit and collection receptacle comprising a casing fixed in a wall or other support and opening through opposite sides thereof, said casing having a longitudinal groove on the inside containing longitudinally spaced shoulders, a receptacle slideable in the casing, and a latch carried by the receptacle and adapted to extend into the groove to engage either of the shoulders.

3. A deposit and collection receptacle comprising a support having an opening through opposite sides thereof, a slideable receptacle in the opening, and a latch carried by the receptacle, the opening in which the receptacle is mounted having a stop engageable by the latch to limit the extent of the withdrawal of the receptacle from one end of the opening, and said opening having another stop engageable by the latch when the receptacle is housed in the opening to lock the same against withdrawal from the aforesaid end of the opening.

25 4. A deposit and collection receptacle comprising a support having an opening through opposite sides thereof, a slideable receptacle in the opening, and a latch carried by the receptacle, the opening in which the receptacle is mounted having a stop engageable by the latch to limit the extent of the with-

drawal of the receptacle from one end of the opening, and said opening having another stop engageable by the latch when the receptacle is housed in the opening to lock the same against withdrawal from the aforesaid end of the opening, said latch being accessible from the other end of the opening only.

5. A deposit and collection receptacle comprising a support having an opening through opposite sides thereof, said support having longitudinally spaced shoulders, a receptacle slideable in the opening, and a latch carried by the receptacle and adapted to abut against either of the aforesaid shoulders.

6. A deposit and collection receptacle comprising a support having an opening through opposite sides thereof, the wall of said opening having a longitudinal groove containing longitudinally spaced shoulders, a slideable receptacle in the opening, and a latch carried by the receptacle and adapted to extend into the groove to engage either of the shoulders.

In testimony whereof I affix my signature in presence of two witnesses.

HARRY J. RICKERT.
